COMBINED TYPEWRITING AND COMPUTING MACHINE

Henry L. Pitman, Melbourne, Fla., assignor to
Underwood Corporation, New York, N. Y., a
corporation of Delaware

Application January 16, 1948, Serial No. 2,654

11 Claims. (Cl. 235—69.48)

1

This invention relates to combined typewriting and computing machines and more particularly to machines wherein a single keyboard is employed, such as found on ordinary typewriters.

Machines of the type with which this invention is particularly concerned comprise a computing base surmounted by a typewriter cooperating therewith. Within the base are normally contained a plurality of registers located in lateral alignment across the front thereof. For running amounts into the wheels of the registers, there is provided a set of rack bars for each register.

The typewriter carriage is provided with a plurality of column units extending horizontally from the rear thereof, and as the carriage moves into a computing zone corresponding to a column on the work sheet, one of the column units, which may carry a plurality of dogs, depresses a vertically extending plate, thereby selecting one of the registers for operation. If the column unit carries more than one register-selecting dog, then, of course, more than one register will be selected for operation.

The rack bars which actuate the wheels of the registers are provided with indexing pins which are set in accordance with the depression of numeral keys of the typewriter. When a numeral key is depressed, the digit represented by said key is printed and the digit value is also indexed in one of the rack bars. Machines of the character with which this invention is concerned are normally provided with a continuously operating power source and a one-revolution clutch which, when engaged, connects a cycling general operator to the constantly rotating power source. After all of the digits of an amount have been selected, the one-revolution clutch is engaged thereby cycling the machine and running the selected and indexed amounts into the wheels of the selected register or registers.

With machines of the type with which this invention is concerned, it is possible to automatically print totals. That is to say, after one or more amounts have been entered into a register, the amount then standing in the wheels of the register may be automatically read out and printed. For accomplishing this purpose, a set of total-reading feelers is provided for each register and each register wheel is provided with a spiral arrangement of stops. When it is desired to print a total, the set of feelers is released and the individual feelers of the set move forward into engagement with the stops, the amount of forward movement being determined by the particu-

2

lar digits standing in the wheels. These different forward positions of the feelers are then employed in selecting the amount to be printed.

The machine is also provided with a fugitive-
5 one mechanism, making it capable of recording and printing true overdrafts as well as true positive amounts.

The general form of the machine, as set forth above, is well known and is exemplified in my prior Patent No. 2,372,681, among others. The particular embodiment of the machine over which this invention is an improvement is set forth in my copending application Serial No. 494,434, filed July 16, 1943, now Patent No. 2,436,055.

15 In said application Serial No. 494,434, there is illustrated a combined typewriting and computing machine having three register groups, each group comprising two registers. The two registers are obtained for each group by the expedient
20 of interspersing the wheels of the registers so that the wheels of the two registers corresponding to the same denominational order are juxtaposed. One of the two interspersed registers of each group may be selected by laterally shifting
25 the group so that the wheels of one register will be aligned with the register bars when the group is in one lateral position, and the wheels of the other register will be aligned with the register bars when the group is in its second lateral position.

30 As disclosed in said application Serial No. 494,434, the machine has a total capacity of six registers. That is to say, it is possible to work in one group of three registers or another group of three registers. If the groups of registers be
35 designated A, B and C, then group A will contain registers A₁ and A₂, group B will contain registers B₁ and B₂ and group C will contain registers C₁ and C₂. In the machine set forth
40 in application Serial No. 494,434, it is possible to work in registers A₁, B₁ and/or C₁ or in registers A₂, B₂ and/or C₂, but it is not possible to work, for example, in registers A₁ and B₂ at the same time, because all three groups of registers are tied together and are laterally shifted as a unit.

45 By means of the present invention, I have provided three groups of registers, each group containing three (rather than two as set forth above) registers. For convenience, these registers may be designated as above, except, of course, here we have registers A₃, B₃ and C₃ in addition to the other registers.

50 This invention provides means for selecting for computing any one register of any group for

operation at the same time as any one register of any other group. That is to say, in accordance with this invention, it is possible to work for example, or compute, in registers A1, B2 and/or C3 at the same time.

Thus it will be seen that the invention set forth in this application adds considerably to the flexibility of the machine. Not only has the machine's capacity been increased from six registers to nine registers, but it is also possible to compute in more different combinations of registers at the same time.

It is another feature of the invention to provide an improved means for preventing cycling of the machine during the time that relative movement is taking place between a register group and the set of differential actuators for said group.

It is likewise a feature of the invention that all of the register groups are locked in their selected positions while the machine is being cycled so that it will not be possible to accidentally cause a relative movement between a register group and its set of differential actuators during the time that the actuators are in engagement with the wheels of one of the registers of the group.

Another feature of the invention is to provide reliably operative means for preventing release of the total-reading feelers during the time that a relative lateral movement is taking place between a register group and the set of total-reading feelers for said group.

The present invention offers the still further advantage of providing a simple yet reliably operative means for locking all of the register groups in their selected positions during the time that the total-reading feelers are in engagement with the wheels of one of the registers of one of the groups.

These and other objects, features and advantages will more readily appear as the description of one specific embodiment of the invention proceeds.

Referring now to the drawings:

Fig. 1 is a side elevation of a combined typewriting and computing machine, certain parts being shown in cross section and many parts being entirely omitted in order to more clearly show the present invention.

Fig. 2 is a plan view of the mechanism employed for individually shifting each register group independently of the other register groups.

Fig. 3 is a perspective view of part of the mechanism shown in Fig. 2.

Fig. 4 is also a perspective view of part of the mechanism shown in Fig. 2 and constitutes a continuation of Fig. 3.

Fig. 5 is a diagrammatic view of a cam and cam follower structure used in shifting the register groups.

Fig. 6 is a perspective view of the mechanism employed in preventing the machine from being cycled when a register is not fully selected and for preventing the total-reading feelers from advancing when a register is not fully selected and also showing a means for locking the register groups in their selected position while the machine is being cycled or while the total-reading feelers are advanced.

Fig. 7 is an enlarged detail view of certain of the parts shown in Fig. 6.

Fig. 8 is a detail view of certain parts shown in Fig. 7.

Fig. 9 is a perspective view of one of the register groups and certain parts of the tens carry-

over and fugitive-one mechanism, many of the parts having been omitted for greater clarity, and

Fig. 10 is an enlarged perspective view of a portion of the mechanism for returning the registers to their normal or unshifted positions.

Typewriter unit in general

The typewriter unit T is shown in Fig. 1 stripped of all but its bare essentials, since the details thereof have no bearing upon the present invention. The unit T may conveniently be constructed as shown in my prior Patent No. 2,398,395, but it will, of course, be understood that numerous changes as to details may be made without departing from the spirit of the present invention.

Briefly described, the typewriter unit comprises a row of numeral keys 10, any one of which, when depressed, rocks a draw-link 11 into engagement with a continuously rotating snatch roll 12. Upon engagement with the snatch roll, the draw-link 11 is pulled toward the rear of the machine thereby rotating counterclockwise, as viewed in Fig. 1, a lever 13 to which it is pivotally connected. The lever 13 is connected by a link to a pivotally mounted numeral type bar 14, which is rotated clockwise by the counterclockwise rotation of lever 13, to strike the platen 15 carried by a movably mounted carriage generally indicated at 16. The carriage is continuously urged toward the left side of the machine by a spring motor generally indicated at 17 and, upon actuation of a type bar 14, an escapement mechanism generally indicated at 18, which may be of any desired construction, is operated to permit the carriage to move one letter space to the left.

Computing base in general

The typewriter unit T surmounts and cooperates with a computing base generally indicated in Fig. 1 at B. The computing base comprises in general three sets of differential actuators consisting of pin bars 19 carrying rack teeth 20 on the forward ends thereof. Permanently in mesh with the rack teeth are idler wheels 21. Groups 22 (Fig. 9) of computing wheels 23 are movable into engagement with the idlers for subtraction or into direct engagement with the differential actuators for addition, as will presently be more fully explained.

The differential actuators are normally positioned so that digit pins 24 carried thereby are out of operative alignment with a group of pin setting bars generally indicated at 25.

Register group selection

The typewriter carriage 16 is provided with a column unit, generally designated 26, extending horizontally from the rear thereof. There is one column unit for each zone in which a column of figures is to be printed. Each column unit is provided with one or more register group selecting dogs 27 and with a denomination selecting tooth 28. As the carriage is tabulated into a column printing zone, the register group selecting dog 27 depresses a plate 29, which, through well-known connections such as shown in Patent No. 2,400,949, issued May 28, 1946, to R. W. Pitman, and shown here only in dot-and-dash lines, raises a group of couplers 30 to a position such that when the couplers are moved forward, they will push the differential actuators forward to operatively align the pins 24 with the pin setting bars 25.

The couplers are pivotally connected to a set of distributive racks 31 which are individually articulated to a set of transverse blades, not shown. Also connected to said transverse blades are a set of master racks 32 which are pushed forward seriatim by a set of bell cranks 33. For operating the bell cranks 33, there is provided a set of push rods 34 which are actuated by a universal set of vertical jacks 35.

As the typewriter carriage traverses a computing zone, the denomination selecting tooth 28 depresses one of the vertical jacks 35 at each letter space. The jack in turn, through the push rod 34, operates the bell crank 33 to move one of the master racks 32 forward and, through their connections with the transverse blades, one of the distributive racks 31 for each of the groups of registers is moved forward. If a register group has been selected for operation by raising the couplers 30 for that register group, one of the pin bars 19 will be moved slightly forward to align the pins 24 with the pin setting bars 25. Then upon operation of one of the numeral keys 18, a pendant member 36 on the lever 13 will be moved downward to engage a crank arm, not shown, on a rack shaft 37 to thereby depress the corresponding pin setting bar 25 and push one of the pins 24 through the bar 19. After the pin has been set in a bar 19, the carriage steps one letter space to the left, thereby releasing the jack 35 and allowing the bar 19 to be moved to the rear by a spring 38, and the operation is repeated for each digit of the number. Thus it will be noted that when a numeral key 18 is depressed at a time when the carriage is in a computing zone, the digit corresponding to that key will be printed and the pin 24 corresponding to the digit will be set. The details of construction of the above described indexing mechanism are more fully explained in my prior Patent No. 2,202,671.

After all the digits of a number have been indexed in the bars 19, the next step is to run the number into the wheels of the selected register or registers, and for this purpose, a general operator bar 39 is employed. The bar 39 is operatively connected, as described in my prior Patent No. 2,168,538, to a side plate 40, Figs. 1 and 6, which in turn is connected by a crank 41 to a shaft 42, Fig. 6. After the lowest order digit has been indexed as described above, the carriage steps to the space next beyond the lowest order space whereupon the tooth 28 depresses a jack, not shown, but similar to denominational jacks 35, to raise a latch arm 35', Fig. 2, and thereby cause a one-revolution clutch diagrammatically illustrated at 43 to become engaged as described in my prior Patent No. 2,178,702. Engagement of clutch 43 connects the shaft 42 to a source of power, not shown, whereupon the shaft is driven through one complete revolution at which time the clutch is automatically disengaged. Rotation of the shaft 42 causes the crank 41 to move the side plate 40 and thereby the general operator bar 39 from the position shown in Fig. 1 toward the front of the machine and back to the Fig. 1 position, all as more particularly described in my prior Patent No. 2,168,538 referred to above.

As the general operator bar 39 is moved forward, it picks up any of the bars 19 in which an index pin 24 has been set, or pushed through, and moves the bar 19 so picked up toward the front of the machine. The rack teeth 29 rotate the idler wheels 21. If the computing wheels 23

have been moved into direct engagement with the rack teeth 29, in a manner such as set forth in my copending application Serial No. 494,434, said wheels will be rotated in an additive direction by an amount corresponding to the digits indexed in the bars 19. Likewise if the computing wheels 23 are moved into engagement with the idlers 21, then upon forward movement of the bars 19, the computing wheels will be rotated in a subtractive direction. Whether the wheels of a register group move into an additive or subtractive position is determined by the position of a state control slide, partially shown in Fig. 1 at 44. State control slide 44 is continuously urged toward the front of the machine by a spring and is released for forward movement by carriage controlled latches, not shown, as more fully described in my prior Patent No. 2,118,860.

Tens carryover

As described in my copending application Serial No. 494,434, the general operator bar 39 is provided with a series of pivotally mounted levers only partially shown herein at 45 and as the general operator bar moves forward, it is the upper ends of these levers which actually come in contact with the set index pins 24. When a computing wheel 23 rotates through a transfer point, it is operative, as will be described later, to rock counterclockwise, Fig. 1, a lever 46, which in turn raises the forward end of a bar 47 from latching engagement with a transverse bar 48. Bar 47 is pivotally connected to a stationarily fulcrumed lever partially shown at 49, and corresponding to lever 86 in my copending application Serial No. 494,434. Upon its disengagement from transverse bar 48, the carryover bar 47 is moved forwardly by its spring 50 and thereby turns lever 49 counterclockwise so that an end of said lever is in the path of an end of lever 45 to cause lever 45 to be rocked counterclockwise when the two levers come into engagement. This rocking of lever 45 relative to the general operator bar moves the next higher bar 19 an extra carryover step forward, all as more fully set forth in my copending application Serial No. 494,434. The levers 46, bars 47, levers 49 and levers 45 thus constitute a set of carryover devices.

Register group details

In the machine of this invention, instead of providing three registers across the front of the machine as shown in my prior Patent No. 2,372,681, I have here provided three register groups, each group consisting of three registers. Since the details of construction of the register groups per se are substantially identical with the register groups of my copending application Serial No. 494,434, reference is hereby made to said application for those details.

Referring now to Figure 9, a group of computing wheels, only one of which is shown, is generally indicated at 22. The individual wheels 23 of the group are coaxially mounted for independent rotation on a shaft 51. The shaft 51 is rigidly secured to a pair of side plates 52 and projects beyond said plates for a reason which will presently become apparent. Rigidly attached to each wheel 23, so that it may be considered a part thereof, is a disk 53 carrying a spiral array of stops as fully explained in my copending application Serial No. 494,434.

To more securely hold the plates 52 together and form a frame for the group of register wheels,

cross rods 54 and 55 are secured between said plates. On the rod 55 is mounted a detent pawl 56 for each wheel 23. The pawl 56 is urged by a spring 57, anchored to a saddle 58 on cross rod 54, toward the wheel 23 so that a curved end portion of the pawl lies between the teeth of the wheel to thereby constitute a drag on said wheel and prevent the wheel from being inadvertently turned due to frictional engagement with an adjacent wheel which is being deliberately operated. The pawls 56 also serve the additional function of indicating when a register is clear, as explained in my aforesaid copending application Serial No. 494,434.

Also mounted upon rod 55 is a carryover trip lever 59 for each computing wheel which is urged toward the wheel 23 by a spring 60 anchored to saddle 58. The lever 59 is provided with a tail portion 61, for a purpose to be presently described, and with a portion 62 which lies in the rotative path of a carryover pin 63 forming a part of wheel 23, and mounted in the disc 53 thereof.

As described above, and as will be readily apparent from an inspection of Figs. 2 and 6, there are provided in the present machine three sets or groups of registers aligned transversely across the front of the machine. Each group of registers is individually mounted between a pair of mounting plates 64 (see Fig. 3) fixed to the base of the machine. Extending between the mounting plates 64 is a shaft 65, Fig. 1, upon which are rotatably mounted the idler wheels 21 referred to above.

Between the mounting plates 64 is a frame consisting of plates 66 secured together by a cross shaft 67 and a tie-rod 68 and it is this frame in which the register group is supported. Each plate 66 is provided with a vertical slot 69 open at the top and into which the extended ends of shaft 51 are loosely fitted. Each plate 66 is also provided at the rear thereof with a horizontal slot 70 which fits about a roller 71 mounted upon the idler wheel shaft 65. The frame comprising the plates 66 can be rocked downwardly about the rollers 71 as an axis by depression of a bifurcated tongue 72, Fig. 9, the slotted end of which straddles the cross shaft 67. Downward movement of the frame plates 66 will result in the computing wheels 22 being meshed with the rack teeth 29 as will be evident from an inspection of Fig. 1. To place the wheels 22 in engagement with the idlers 21, the frame plates 66 are moved rearwardly so that the rollers 71 are positioned in the bottom of the horizontal slots 70. Plates 66 are moved rearwardly by the links partially shown at 73.

The tongue 72 and the links 73 are selectively connectable to a shaft, a partial cross section of which is indicated at 74 in Figure 1. Since the specific arrangement whereby the computing wheels are moved to additive or subtractive position forms no part of the present invention, the arrangement is not shown in the present drawings but reference may be had to my copending application Serial No. 494,434 for the details thereof, it being sufficient to state here that the selective engagement of the wheels for addition or subtraction is determined by the position of state control slide 44.

In each register group there are three computing wheels 23 for each denominational order. All the wheels of the group are mounted upon the shaft 51 and the three wheels for each order are juxtaposed. A register group may then be said to consist of three registers which are

operable in three different lateral positions. For placing the register group in its three lateral positions, the plates 52, carrying the shaft 51 and wheels 22, are shiftable by a means to be presently explained, it being sufficient here to state that the shaft 51 and cross rod 55 slide longitudinally through the frame plates 66. There is a detent pawl 56 and a carryover trip lever 59 for each wheel 23 and these members are, of course, longitudinally movable with the computing wheels.

There is one carryover bar 47 and one carryover lever 46 for each of the register bars 19. As seen in Fig. 9, the levers 46 are provided with

rounded upper end portions 75. As the register group is positioned in its different lateral positions, one of the carryover trip levers 59 for each group of three wheels will become aligned with the rounded portion 75 of one of the trip levers. As a wheel 23 moves from 9 to 0 or from 0 to 9, the pin 63 will contact the portion 62 of carryover trip lever 59 to thereby rock said lever and cause the tail portion 61 thereof to rock the lever 46 counterclockwise, Fig. 1, about the shaft 67. Rocking of a carryover lever 46 causes a carryover bar 47 to be lifted from latching engagement with the transverse bar 48 to thereby cause a tens transfer to the next highest order wheel, as previously pointed out.

In order that an extra unit may be added to or subtracted from the lowest order wheel when the register passes through zero from a positive amount to a negative amount or from a negative amount to a positive amount, the carryover lever 46 for the highest denominational order is connected by a bail 76 to a carryover bar operating portion 77. When the highest order wheel passes through the transfer point, that is from 9 to 0 or 0 to 9, the carryover lever 46 for that order is rocked to thereby move bail 76 and carryover bar engaging portion 77. The portion 77 unlatches the carryover bar 47 corresponding to the lowest order wheel which through the arrangement described above causes the denominational operator bar 19 corresponding to the lowest order to move forward an extra digital amount to thereby turn the lowest order wheel an extra amount equivalent to one digit.

Automatic total printing

After several columns of figures have been typed on a work sheet, some of the columns containing debit entries and other credit entries, it is desirable that the totals of the various columns be printed. In order that these totals may be automatically read out of the registers and printed, the present machine is equipped with total taking mechanism such as fully described in my prior Patent No. 2,398,395.

Briefly described, the total taking mechanism comprises a set of feelers 78, Figs. 1 and 2, which are normally held in their rearmost or retracted position by a universal restorer bar 79. When it is desired to take a total, a "total" key, not shown, is depressed, whereupon the carriage is tabulated to the next columnar position and the carriage operates a latch, as will be more fully described later, to release the bar 79 for forward movement under the influence of a spring 79', Fig. 6.

The feelers 78 are arrested at various stages of forward movement corresponding to the digits standing in the wheels of the aligned register by contact with the stops on the disks 53 of wheels 23. It is to be understood that there

is provided one feeler 78 for each denominational order and that as a register group is laterally shifted to its different positions, one or another of the sets of juxtaposed wheels will be aligned with the feelers. After the feelers have moved forward, plates 80, Fig. 1, are raised seriatim to raise an arm 81 pivoted at the rear of each feeler to thereby lift one of a series of blades 82 and close one of the switches 83. The closing of a switch 83, corresponding to a digit being sensed by the feeler 78, causes a solenoid 84 to be energized and through its armature 85 raise the draw-link 11, corresponding to the sensed digit, into contact with the snatch roll 12. Engagement of the draw-link 11 with the snatch roll will, of course, cause the corresponding digit to be printed. After all of the digits have been printed, the machine is cycled, during which time the total-reading feelers are returned to normal position as is well known.

Lateral register selection

For shifting the register groups laterally to operatively align the wheels of one or another of the registers of the group with the differential operators and the total-reading feelers, each group is provided with a shipper member 86, as most clearly shown in Figs. 2 and 6. The shipper member 86 is provided with a pair of downwardly extending ears 87 at the front thereof fitting lightly against the outsides of side plates 52 of the register group frame. The ears 87 do not press against the plates 52 but are located in close proximity thereto. The ears 87 therefore do not interfere with the free downward or rearward movement of the plates 52 when the register group is moved to an additive or subtractive position.

Each of the shipper members 86 is slidably mounted upon a pair of brackets 88 having retaining screws 89 extending through elongated slots 90. The brackets 88 are fixed to a stationary cross member 91 of the machine. A resilient means in the form of a tension spring 92 is secured at one end to a lug 93 on said shipper member and fixed at the other end to one of the brackets 88 so as to constantly urge the shipper member to the left, as seen in Fig. 2.

For retaining the shipper member 86 in its normal position, which is as shown in Fig. 2, that is to the right, a retaining means in the form of a rotatable member 94 is provided. The rotatable member 94 has steps on the periphery thereof and the shipper member 86 has a downwardly extending pin 95, Fig. 5, for engaging said peripheral steps. Rotation of the member 94 will bring the different steps on the periphery thereof into operative relation with said pin and the spring 92 will move the shipper member 86 toward the left, as viewed in Fig. 2, step by step in accordance with the rotative position of member 94. Due to the engagement of the ears 87 with the sides of plates 52, the register group is moved laterally by the shipper member 86 to align the wheels of different registers of the group with the differential actuators, as will readily be understood.

Each of the members 94 is rigidly secured to one end of a staff 96, to the other end of which is secured a pinion 97. The pinions 97 are in mesh with, and are operated by, racks 98 provided upon the forward ends of slides 99, 100 and 101, as best seen in Figs. 2 and 3.

The slides 99, 100 and 101 are supported and guided at their front ends by a cross member

102 mounted upon the machine frame and having slots therethrough for accommodating said slides. At their rear ends, the slides are supported and guided by brackets 103, only one of which is shown (see Figs. 2 and 4), secured to the framework of the machine and provided with a pair of headed screws 104 for engaging the sides and bottom portion of the slides.

Each slide is individually urged toward the front of the machine by a resilient member in the form of a spring 105. The slides are normally retained in their rearmost positions by a pair of latches, as will presently be described.

The slide 99 is provided with a pair of open latch slots 106 and 107 located near the rear end thereof. The slot 107 is considerably longer than the slot 106, as may be seen in Fig. 2. In the slot 106 is normally positioned a latch member 108, slidably guided at its lower end in bracket 103 which also supports and guides the slide 99, as previously pointed out. The latch member 108 has a pin-and-slot operating connection with a T-shaped lever 109 which is pivotally mounted on a stub shaft 110 and urged in latch engaging clockwise direction by a spring 111. One end of the lever 109 is engaged by a second lever 112 at 113. The second lever 112 is pivotally mounted upon a shaft 114 and connected by a link to a bell crank 116 mounted upon a shaft 117. Resting within an open slot in one arm of the bell crank 116 is a push rod 118 engaged at its upper end by a plate 119, which plate in turn supports a selector plate 120.

When a selector plate 120 is depressed by a dog 120', similar to the dog 27 and carried by the column unit 26, the latch member 108, through the chain of rods, links and levers described above, is withdrawn from the slot 106. Withdrawal of the latch member 108 from slot 106 allows the spring 105 to pull slide 99 forward until the back of slot 107 engages a latch member 121 similar to latch member 108. Forward movement of slide 99 causes its rack 98 to rotate pinion 97, which in turn rotates member 94 and thereby allows spring 92 to laterally move the register group to align a second set of computing wheels with the differential operators. The group of registers so moved may for convenience be referred to as the "A" group, and it may further be considered that whereas the No. 1 register of "A" group was previously operatively aligned with the differential actuators, the No. 2 register of "A" group is now aligned with the actuators.

For operating the latch 121, I have provided a T-shaped member 122 urged in a latch engaging clockwise direction by a spring 123. The T-shaped member 122 is pivotally mounted upon the stub shaft 110 and one of its arms is engaged by a lever 124 pivotally mounted upon shaft 114 and connected by a link to a bell crank 125 mounted upon shaft 117. One arm of bell crank 125 is provided with an open slot for receiving a rod similar to rod 118 and the rod is operated through a pair of plates similar to the plates 119 and 120. Depression of plate 120 corresponding to bell crank 125 will cause a counterclockwise oscillation of lever 122 to withdraw latch member 121 from elongated slot 107. Upon withdrawal of the latch member from slot 107, the slide 99 is again drawn forward by the spring 105 to cause a further rotation of pinion 97 and retaining member 94 and thereby allow spring 92 to move the register group another lateral step toward the left. It will be apparent that the No.

3 register of "A" group is now operatively aligned with the differential actuators and the total-reading feelers.

Before an amount may be entered into any of the registers of the "A" group or a total printed from any of the registers of the group, the plate 29 previously referred to must be depressed. When plate 29 is depressed, a rod similar to rod 118 is moved downward to rock a bell crank 126 and through a member partially shown at 127 the couplers 30 corresponding to the differential actuators for the "A" group are raised.

The "B" register group is selected for operation by depressing a plate 29, which, through a rod similar to rod 118, rocks a bell crank 128 and, through the member partially shown in Fig. 4 at 129, lifts the couplers 30 corresponding to the "B" group.

The slide 101 controls the lateral position of the "B" register group and this slide, similarly to slide 99, is provided with a pair of slots in its rear end portion, and since they are identical with the slots 106 and 107 of slide 99, they have been given the same reference numerals.

Normally extending into the slot 106 is a latch member 130 similar to latch member 108. Connected to the latch member 130 is a generally T-shaped lever 131, said lever being urged in a latch engaging counterclockwise direction by a spring 132. One arm of said lever is engaged by a second lever 133, which is pivotally mounted upon the shaft 114 and connected by a link to a bell crank 135 pivotally mounted upon the shaft 117. An open slot in one arm of bell crank 135 receives one end of a push rod 137 similar to push rod 118. Through a plate similar to plate 119, the push rod 137 is operatively connected to a selector plate similar to plate 120. Upon depression of selector plate 120 corresponding to bell crank 135, the latch member 130 is withdrawn from the latch slot 106 in slide 100 through the train of rods, links and levers described above. Withdrawal of latch member 130 causes the slide 100 to be drawn forward by its spring 105 until the rear edge of slot 107 in said slide comes into contact with a second latch member 138. Forward movement of slide 100 causes its rack 93 to rotate pinion 97, which in turn rotates member 94 and thereby allows spring 92 to laterally move the register group to align a second set of computing wheels with the differential actuators. Instead of the No. 1 register of "B" group being operatively aligned with the differential actuators, the No. 2 register of said group is now aligned with said actuators.

Withdrawal of latch member 138 from slot 107 in slide 100 will result in the "B" register group being shifted to a third position wherein the wheels of the No. 3 register will be aligned with the differential actuators, as will readily be understood. For lifting latch member 138 to withdraw it from its slot 107, a generally T-shaped lever 139, normally urged in a latch engaging counterclockwise direction by a spring 140, is provided. One arm of the lever 139 supports a lever 141 connected by a link to a bell crank 142 pivotally mounted upon shaft 117. An open slot in one arm of bell crank 142 supports a push rod similar to rod 137, which, through a plate similar to plate 119, is operatively connected at its top end to a plate 120. Depression of the plate 120, corresponding to bell crank 142, will result in withdrawal of latch member 138, as will readily be understood.

The "C" register group is selected for opera-

tion by depressing a plate 29, which, through a rod similar to rod 118, rocks a bell crank 143 and, through the member partially shown at 144, lifts the couplers 30 corresponding to the "C" group.

The slide 101 controls the lateral position of the "C" register group and this slide, similarly to slides 99 and 100, is provided with a pair of slots 106 and 107 in its rear end portion.

Normally extending into the slot 106 is a latch member 145 similar to latch members 108 and 130. Operatively connected to latch member 145 by a pin-and-slot connection is a bell crank 146 pivotally mounted upon a stub shaft 147 and urged in a latch engaging direction by a spring 148. One arm of said bell crank is connected by a long link 149 to a generally T-shaped lever 150. One arm of said T-shaped lever is operatively connected to a lever 151 pivotally mounted upon shaft 114 and connected at one end through a link to a bell crank 152 pivotally mounted upon shaft 117. An open slot in one arm of bell crank 152 receives one end of a push rod similar to push rod 137, which is operatively connected through a plate similar to plate 119 to a selector plate 120. As will be readily understood, depression of the plate 120 corresponding to bell crank 152 will, through the train of rods, links and levers above described, result in withdrawal of latch member 145 from slot 106 in slide 101. Withdrawal of said latch member will, of course, permit the spring 105 to move the slide 101 forward until the rear edge of slot 107 contacts a second latch member 153. This forward movement of the slide 101 will, of course, rotate the member 94 and permit spring 92 to move the "C" register group laterally to a position wherein the No. 2 register of said group is operatively aligned with the differential actuators for said group.

Since the train of mechanism for operating latch member 153 is identical with that for operating latch member 145, no detailed description thereof is thought to be necessary. It will be readily apparent that when the latch member 153 is withdrawn from the slot 107, the "C" register group will be moved laterally to a position wherein the No. 3 register thereof will be operatively aligned with the differential actuators and the total-reading feelers for that group.

It is to be understood that my invention is not limited to the use of three registers per group or to three groups of registers. If it is desirable to employ only two registers in a group, one of the latch members for the slides 99, 100 and/or 101 may be removed, or if it is found desirable to employ more than three registers in a group, additional latch members may be provided.

60 *Returning registers to normal position*

To return a laterally shifted register group to its normal position wherein the No. 1 register of the group is operatively aligned with the differential actuators and the total-reading feelers, the control slide 99, 100 or 101 for said group is moved toward the rear of the machine. Rearward movement of a slide 99, 100 or 101 causes its rack 93 to rotate pinion 97 in the direction opposite to that in which it had been rotated upon forward movement of the slide. This rotation of pinion 97 will cause the member 94 to be rotated in a counterclockwise direction as viewed in Fig. 5. The steps on the periphery 75 of member 94 flow smoothly into each other so

that as said member is rotated in a counter-clockwise direction to return to its normal, or Fig. 5, position, the shipper member 86 through the pin 95, and consequently the register group, is returned to its normal position.

For moving the slides 99, 100 and 101 to the rear after they have been moved forward as aforesaid, a universal restorer bar 154 is employed. As will presently be described, the restorer bar 154, shown in Figs. 1, 2 and 3 in its normal position, is moved toward the rear of the machine during the later part of a cycle. During the rearward movement of bar 154, it hits against a pin 155, with which each of the slides 99, 100 and 101 is provided, on any of said slides which may have been moved forward, thereby picking up said slide and moving it toward the rear. When a slide reaches its home position, any of the latch members which have been lifted will be snapped down into latching position by the spring on the latch operating member, as previously described.

It will be remembered that at the time of instituting a cycle, the carriage has moved to a leftward position whereat none of the register shifting cam plates 120 are depressed and that, therefore, there will be nothing to prevent the latches from being operated by their respective springs.

Thus it will be seen that the rotatable member 94 constitutes a means for maintaining the register group in its normal position and also a means for returning the register group to its normal position after same has been laterally shifted.

For moving the restorer bar 154 toward the rear, said bar has secured thereto a pair of arms 156 which are pivotally connected at their forward ends to a pair of levers 157 secured upon a shaft 158. Only a part of shaft 158, and one of the levers 157, is shown but it is to be understood that said shaft extends entirely across the machine and that the two levers 157 are identical. Also secured to shaft 158 is a lever 159 having pivotally attached thereto a hook-link 160. The rear end of link 160 is provided with a slot 161 into which a pin 162 extends.

The pin 162 is carried by an arm 163 pivotally mounted upon a stationary stud 164. Also pivotally mounted upon stud 164 is an arm 165 provided with a landing 166, as seen in Fig. 10. The free ends of arms 163 and 165 are urged together by a relatively strong spring 167 but are held apart, as shown in Fig. 10, by a pin 168 on arm 163 resting upon the landing 166 of arm 165. A roller 169 is mounted upon the side plate 40 and when the machine is not being cycled, the roller 169 is positioned upon ledge 170 at the top of landing 166, at best seen in Fig. 10. A latch 171 is pivotally mounted upon a stationary stud 172 and is urged in a clockwise direction, as viewed in Fig. 1, by a spring 173. When the roller 169 is in its normal position, it is in abutment with a shoulder 174 on latch 171. A spring 175, lighter than spring 167, urges the arm 163 in a clockwise direction, as viewed in Fig. 1, to hold the ledge 170 against roller 169.

When the machine is cycled, the side plate 40, which as previously pointed out is operatively connected to the general operator bar 39, is moved toward the front of the machine and then back to the Fig. 1 position. Forward movement of side plate 40 carries the roller 169 forward and upon the first slight forward movement, said roller moves away from shoulder 174 allowing spring

173 to move the latch 171 into engagement with a cooperating part 176 on arm 163. As the roller continues to move forward, spring 175 rocks arm 163 and, through the spring 167, arm 165, upwardly to keep landing 166 in engagement with said roller until hook-link 160 contacts the bottom of the general operator bar 39. After roller 169 leaves the landing 166, the general operator bar 39 and hook-link 160 are in sliding contact and a slight additional forward movement of bar 39 will allow spring 175 to rock the arm 163 and, through pin 162, the hook-link 160, upwards to a point where a shoulder 177 on said hook-link will be behind the general operator bar. This additional movement of arm 163 will allow the latch 171 to be moved by its spring 173 underneath the cooperating part 176.

As the general operator bar 39 nears the completion of the second half of its cycle, it contacts shoulder 177 on hook-link 160 and moves said link toward the rear. Rearward movement of link 160 causes the restorer bar 154 to be moved rearward as aforesaid through the levers 159 and 157 and arms 156. During the later part of the cycle, the roller 169 contacts the landing 166 and presses the arm 165 downward. Downward movement of arm 165 tensions the heavy spring 167 but does not move the arm 163 downward because arm 163 is latched up by the latch 171. At the very end of the cycle, the roller 169 contacts the shoulder 174 to rock the latch 171 in a counterclockwise direction, as viewed in Fig. 1 to thereby release arm 163 for downward movement under the influence of spring 167 which, as previously pointed out, is stronger than spring 175. This downward movement of the arm 163 results in releasing the shoulder 177 from the back of the general operator bar 39, and the restorer bar 154 is thereupon returned to its normal position by a spring 178.

Cycle prevention during register shifting

In order to prevent jamming of the machine or damage to any of the parts thereof, it is important that cycling be prevented during the time that a register group is being laterally shifted. If the cycling clutch 43 should become engaged and thereby cause forward movement of the general operator bar 39 at a time when the wheels of none of the registers of the selected group were properly aligned with the differential actuators, it is readily apparent that, at best, an inaccurate computation would be made.

In order that cycling will be prevented at all times when a register group is not in its fully selected position, the following mechanism is provided. A member 179, having a pair of notches 180 at one end thereof, is operatively connected to each of the register groups. The members 179 are slidably guided upon the stationary cross member 91 by means of a pair of pins or screws 181 fixed to the cross member 91 and extending through a pair of elongated slots 182 in the members 179. For each of the register groups, a motion multiplying lever 183 is pivotally mounted upon one of the shipper guiding screws 89 and has a pin-and-slot connection 184 with said shipper member and a pin-and-slot connection 185 with one of the slides 179. Thus it will be apparent that when one of the shipper members 86, and consequently one of the register groups, is laterally shifted, the corresponding member 179 will likewise be shifted but by a slightly greater extent due to

the motion multiplying lever 183. In some instances, it may be desirable to omit the motion multiplying lever 183 and connect the members 179 directly to the shipper members 86.

A second member 186 extending transversely of the members 179 is slidably guided at its forward end by a screw or pin 187 fixed to the cross member 91 and extending through an elongated slot 188 in member 186. Member 186 is urged toward the front of the machine by a spring 189 and at its forward end is provided with an arm 190 carrying a feeler 191 for a purpose to be presently described.

At its rearmost end, the member 186 is provided with an extension 192 pivotally connected at 193 to a member 194. The member 194 is pivotally mounted upon a shaft 195 and connected by a bail 196 to a finger 197.

Normally the spring 189, above referred to, due to the connections between the member 186 and the finger 197, holds the finger 197 lightly pressed against a stud 198 carried by a clutch closing plate 199. The plate 199 corresponds to the plate 93 of my prior Patent No. 2,178,702 and, as explained in said patent, the stud 198 must be released by the latch arm 35', Fig. 2, and be rotated in a clockwise direction, as viewed in Fig. 7, before the cycling clutch is engaged.

If all the register groups are in one of their fully selected positions, either the notches 180 in the members 179 will be aligned with the feeler 191 or the members 179 will be moved to the left far enough so that the ends thereof will be entirely out of the path of movement of the feeler 191. If on the other hand, a register group should not be in a fully selected position, then the side of the corresponding member 179 will be in the path of the feeler 191. If during the time of this non-fully selected position of any register group, the clutch pawl 35' should be tripped, the clutch closing plate would attempt to rotate clockwise in order to engage the clutch but the stud 198 would be unable to move the finger 197 because, as above described, the finger 197 is operatively connected to the feeler 191 and the feeler 191 would abut the side of one of the members 179 and, therefore, be unable to move toward the rear far enough for the stud 198 to get past the engaging end of finger 197. Thus it will be seen that I have provided means in part connected to the register groups for preventing cycling at all times when the wheels of none of the registers of any of the groups are operatively aligned with the differential actuators.

Register shifting prevention during cycling

If all the register groups are in any one of their fully selected positions, then as pointed out above, either the notches 180 will be aligned with the feeler 191 or one or more of the members 179 will be located far enough to the left so that its end is out of the path of movement of the feeler 191. If under these conditions, the latch arm 35' is removed from the stud 198, the plate 199 will rotate in a clockwise direction, as viewed in Fig. 7, and the stud 198 will cam the finger 197 toward the rear. Rearward movement of the finger 197 will result in rearward movement of member 186 against the action of its relatively light spring 189 and place the feeler 191 within one or the other of the notches 180 or move it to a position rearwardly of the front edge of one of the members 179 thus lock-

ing all of the register groups in their selected positions.

In order that the registers will remain locked during the forward and rearward movement of the differential actuators, the cycle shaft 42 is provided with a holding cam 200, and the extension 192 is provided with a roller 201. When the finger 197 is moved to the rear, as aforesaid, the extension 192 is, of course, likewise moved rearwardly and the roller 201 is moved far enough to the rear so that as the shaft 42 rotates, the holding cam 200 will be moved underneath the roller 201 to hold extension 192 and consequently the member 186 in their rearmost positions. This will, of course, maintain the feeler 191 in its rearmost position and maintain the register groups in a locked condition. When the cycle of the shaft 42 is approximately three quarters completed, the general operator bar 39 has completed its movement of the differential actuators, and at that point a second cam 202 on the shaft 42 picks up a roller 203 on the extension 192 and returns the finger 197 into the path of the stud 198 and also returns the member 186 and the feeler 191 to their forward or unlocking positions. Thus it will be seen that I have provided means for locking the register groups in their selected positions during a cycle.

Prevention of automatic total taking during register shifting

As previously explained, with the present machine it is possible to automatically print the total standing in any of the registers. For taking a total, a reed, not shown, has an operative connection with a shaft 204, Fig. 6, and when the reed is depressed by column unit 26, the shaft 204 is turned in a clockwise direction, as viewed in Fig. 6. As explained in my prior Patent No. 2,372,681, previously referred to, clockwise rotation of shaft 204 serves to withdraw a latch arm 205 fixed thereto from latching engagement with a slide 206. Also, as explained in said patent, the slide 206 is pivotally connected to an arm 207 fixed to one end of a cross shaft 208. The cross shaft 208 has fixed to its other end an arm 209 to which is pivotally connected a member 210. The slide 206 and the member 210 have fixed therebetween the previously mentioned feeler restorer bar 79 and when latch arm 205 is withdrawn, the spring 79' draws the feeler restorer bar 79 toward the front of the machine thereby freeing the total-reading feelers for forward movement.

In order that the feeler restorer bar may not move forward and consequently the feelers may not move forward into engagement with the register wheels except when all the register groups are in a fully selected position, the following mechanism is provided. To the arm 209 is pivotally attached a member 211 having a latch notch 212 therein. Normally extending into said latch notch is a latch member 213 pivotally connected at 214 to an arm 215 fixed to a cross shaft 216. Also fixed to said cross shaft is an arm 217 having a stud 218 normally engaged by, and held up in its Fig. 6 position by, a latch arm 219 fixed to the aforementioned shaft 204. Likewise fixed to the cross shaft 216 is an arm 220 urged downwardly by a spring 221 and carrying a stud 222 on the free end thereof. For cooperating with the stud 222, a dog 223 loosely mounted upon a cross shaft 224 is provided. The dog 223 is provided with a shoulder having a rounded portion 225 and a land 226 and has an upward

extension 227 extending through a slot 228 in the member 186. The dog 223 is normally held in a position such that the rounded portion 225 is under the stud 222 on arm 220 by an arrangement to be presently explained.

If it is desired to automatically print the total standing in any one of the registers and all of the register groups are in a fully selected position, a "total" reed is depressed to thereby rock the shaft 204 clockwise of the Fig. 6 position, as explained in my prior Patent No. 2,372,681 referred to above. Such clockwise rocking of shaft 204 removes the latch arm 205 from engagement with the slide 206 to condition the restorer bar 79 for forward movement under the influence of spring 79'. Clockwise rocking of shaft 204 also removes the latch arm 219 from engagement with the stud 218 on arm 217. Thereupon the spring 221 pulls the arm 220 downwardly and rocks cross shaft 216 in a clockwise direction, as viewed in Fig. 6, to thereby withdraw the latch member 213 from engagement with the latch notch 212. The spring 79' is then free to pull the restorer 79 toward the front of the machine. The dog 223 does not interfere with the downward movement of arm 220 because, as previously pointed out, the stud 222 is normally resting upon the rounded portion 225 and is only held up by the arm 217 being engaged by latch arm 219.

As the arm 220 moves downward, the stud 222 thereon cams the dog 223 in a clockwise direction, as viewed in Figs. 6 and 7. As the dog 223 moves clockwise, the upward extension 227 on said dog, which is normally located in the rear of slot 228 in arm 186, as seen in Fig. 2, moves toward the rear of the machine. Rearward movement of extension 227 causes rearward movement of member 186 and causes all the register groups to become locked in their selected positions due to the cooperation of feeler 191 and the notches 180, as previously explained.

If any register group is not in a fully selected position at the time it is desired to take an automatic total, the notches 180 will not be in a position to permit rearward movement of member 186, and if the member 186 cannot move rearward, it is obvious that the extension 227 of dog 223 cannot move rearward and, therefore, the arm 220 cannot be moved downward to withdraw the latch member 213 from the latch notch 212. Therefore even though the latch arm 205 is rocked for total taking, the restorer bar 79 and consequently the total-reading feelers 78 cannot move forward because the latch member 213 will prevent the arm 209 from being moved counterclockwise of its Fig. 6 position by spring 79'.

For restoring the parts to their normal positions after a total has been taken, the machine is cycled. During the very first part of the cycle, the shaft 208 is rocked to return the feeler restorer bar 79 and the slide 206 to the Fig. 6 position, as fully explained in my aforementioned Patent No. 2,372,681. A spring 229 acting through an arm 230 fixed upon shaft 204 moves the latch arm 205 down into engaging position. This rocking of the shaft 208 likewise returns the latch slot 212 to a position wherein it may be engaged by the latch member 213, as will readily be understood.

For moving the latch member 213 back into engagement with the latch slot 212, a link 231 is pivotally connected at one end to an intermediate portion of arm 220 and at the other end to an end of a lever 232. The lever 232 is

pivotedly mounted upon a fixed shaft 233 and is provided at its free end with a portion 234 constructed and arranged to be engaged by a pin 235 carried by an arm 236. The arm 236 is connected to the general operator bar 39 and serves to move said bar from its normal Fig. 6 position toward the front of the machine and back to the Fig. 6 position during the cycle, as previously explained. As the cycle gets under way, the pin 235 rocks the lever 232 and through the link 231 the arm 220 is raised. Raising of arm 220 rocks the shaft 216 and moves the latch member 213 down into engagement with the latch notch 212. Rocking of shaft 216 also causes the arm 217 carried thereby to be raised to a position wherein it will be held up by the latch arm 219, as will readily be understood.

Thus it will be seen that means has been provided to prevent the total-reading feelers from moving forward at all times when any register group is not in a fully selected position and conversely means has been provided for locking the register groups in their selected positions during the time that the total-reading feelers are forward.

No automatic total during cycle

During a cycle, if the differential actuators have been indexed, the wheels of any selected 30 register will be rotated, as previously mentioned. It is therefore important that the total-reading feelers be not allowed to move forward into engagement with the computing wheels during the time that the machine is being cycled.

As previously explained, if the arm 220 cannot move down, the total-reading feelers cannot go forward. For preventing downward movement of arm 220 while the machine is being cycled, the following mechanism is provided.

40 A lever 237 is pivotally mounted upon the shaft 195 and has a cammed end portion 238 resting upon the stud 198 of plate 199. The other end of lever 237 has a slot 239 engaging a pin 240 on an arm 241 of a Y-shaped member 242 pivotally mounted upon a shaft 243. Also mounted upon shaft 243 and connected to the Y-shaped member 242 by a bail 244 is an arm 245 carrying a pin 246 for a purpose to be presently explained. A tension spring 247 extends between the bail 244 and a pin 248 carried by a lever 249 which is also pivotally mounted at an intermediate point on the shaft 243. The lever 249 carries a second pin 250 at its opposite end and the pin 250 is engaged within a slot 251 in the dog 223, as most clearly seen in Fig. 7.

When the clutch 43 is tripped for cycling, the plate 199 moves in a clockwise direction, as viewed in Fig. 7, before the clutch actually becomes engaged. Upon the initial movement of plate 199, the lever 237 is rocked in a counterclockwise direction, as viewed in Fig. 7, by the wiping engagement of the stud 198 with the cammed end 238 of said lever. Such counterclockwise rocking of lever 237 will cause the bail 244 to be rocked clockwise, as viewed in Fig. 7, about the shaft 243 as an axis, thereby tensioning the spring 247. As the spring 247 pulls down on the pin 248, the lever 249 is rocked about the shaft 243 and the pin 250, due to its location within the slot 251, rotates the dog 223 in a counterclockwise direction, as viewed in Fig. 7, by an amount just great enough to move the land 226 underneath the stud 222 on arm 220.

75 When the land 226 is underneath the stud

222, removal of latch arm 219 from engagement with the arm 217 will not permit the spring 221 to pull the arm 220 downward because the stud 222 on said arm will have no camming effect upon the dog 223. Thus it will be seen that after the cycle clutch is tripped, the total-reading feelers cannot be made to move forward into engagement with the wheels of any of the registers.

For insuring that the land 226 will be held beneath the stud 222 during the entire cycle, the cycle shaft 42 is provided with a disc 252 having a recess 253 in the periphery thereof. Before a cycle is started, a roller 254, mounted upon an arm 255, is positioned within the recess 253. The arm 255 is pivotally mounted upon the framework of the machine at 256 and is urged in a direction to hold the roller 254 against the periphery of disc 252 by a spring 257.

Pivots connected at one end to the arm 255 is a link 258 having a slot 259 in its other end. The aforementioned pin 246 is positioned within the slot 259.

As the shaft 42 begins to rotate due to engagement of the cycle clutch 43, the stud 198 on plate 199 moves away from the cammed end portion of lever 237 so that the land 226 on dog 223 is no longer held thereby underneath the stud 222. At this point, however, the disc 252 has moved to a position wherein the roller 254 has been cammed out and now rides upon the periphery of said disc. The outward camming of roller 254 has resulted in the arm 255 being rocked clockwise, as viewed in Fig. 7, to pull down on the pin 246 on arm 245 through the link 258. When the end of arm 245, carrying the pin 246, is pulled down, the bail 244 will be rocked clockwise, as viewed in Fig. 7, to thereby hold the spring 247 under tension and hold the dog 223 in its forward position, as will readily be appreciated.

The recess 253 does not return to position of alignment with the roller 254 until the cycle is nearly completed, but to insure that the land 226 cannot get out from under the stud 222 until the cycle is fully completed, a slide 260, best seen in Fig. 6, is provided. The slide 260 is urged toward the rear by a spring 261 and normally abuts the end 262 of the arm 255. One end of the slide 260 is hooked over the restorer bar 154 at 263. It will be remembered that the bar 154 is moved toward the rear during the latter part of a cycle and is returned to its normal position only after the cycle has been fully completed. When the bar 154 is moved to the rear, the spring 261 will move the slide 260 toward the rear by an amount permitted by screw-and-slot connections 264. Rearward movement of the slide 260 will cause it to move underneath the end 262 of arm 255 and hold said arm in its operated position even after the recess 253 has returned to alignment with the roller 254. After the cycle is completed, the restorer bar 154 moves forward and by engagement with the hook 263 moves the slide 260 forward thereby freeing the arm 255 and permitting the spring 257 to pull the roller 254 into the recess 253. The dog 223 is then free to be moved to its rearward position wherein the rounded portion 225 is beneath the stud 222.

For normally positioning the rounded portion beneath the stud 222 of arm 220, the Y-shaped member 242 is provided with a second arm 265 which is operatively connected with a key locking member 266 by a pair of pins 267 fitted against

the opposite sides of said arm. The key locking member 266 is urged toward the front of the machine by a spring 268 and its forward movement is limited by the back of a slot 269 in said member engaging a pin 270.

When the machine is in its normal state, the key locking member 266, through the arm 265, rocks the bail 244 counterclockwise of shaft 243, as viewed in Fig. 7. The bail 244 engages a shoulder on lever 248 at 271, as best seen in Fig. 8, thereby causing the pin 250 on said lever to rock the dog 223 about its supporting shaft 224 by an amount sufficient to move the rounded portion 225 of said dog to a position beneath the stud 222 of arm 220, whereby the parts are conditioned for automatic total taking, as previously explained.

Thus it will be apparent that I have extensively increased the flexibility of the machine shown and described in my copending application Serial No. 494,434; that I have now provided a multiple register machine wherein it is possible to compute in any one of nine registers and in numerous combinations of two or more of said registers; that it is possible to automatically print the total standing in any of the registers and that I have incorporated certain safety features which make it impossible for an inexperienced operator to jam or damage the machine.

Numerous changes may, of course, be resorted to without departing from the spirit of the invention which is limited only by the extent of the following claims.

I claim:

1. In a computing machine, a register group comprising a plurality of juxtaposed wheels for each denominational order, a set of differential actuators comprising an actuator for each denominational order and so arranged that the actuators are normally in operative alignment with one of the wheels of the register group for each denominational order, resilient means urging said register group toward a lateral position for operatively aligning another of the juxtaposed wheels of each denominational order with said set of actuators, retaining means for holding said register group in its normal position, and means for operating said retaining means in such manner that said resilient means may move said register group as aforesaid, said last mentioned means being so constructed and arranged as to also be capable of operating said retaining means in such manner as to restore said register group to its normal position against the action of said resilient means.

2. In a computing machine having a traveling carriage, a register group comprising a plurality of juxtaposed wheels for each denominational order, a set of differential actuators comprising an actuator for each denominational order and so arranged that the actuators are normally in operative alignment with one of the wheels of the register group for each denominational order, resilient means urging said register group toward a lateral position for operatively aligning another of the juxtaposed wheels of each denominational order with said set of actuators, retaining means for holding said register group in its normal position, and means under control of said carriage for operating said retaining means in such manner that said resilient means may move the register group as aforesaid, said last mentioned means being so constructed and arranged as to also be capable of operating said retaining means in such manner as to restore said register

group to its normal position against the action of said resilient means.

3. In a computing machine having a group of registers comprising a plurality of juxtaposed wheels for each denominational order and wherein said group of registers is shiftable laterally to different operative positions, resilient means urging said group of registers in one lateral direction, a rotatable member having steps on the periphery thereof, said steps being located at different radial distances from the center thereof, and cooperating with said group of registers to prevent said resilient means from moving the group of registers in said one lateral direction, and means for operating said rotatable member to bring the different steps on the periphery thereof into operative relation to said group of registers so that said resilient means may move said group of registers laterally step by step in accordance with the rotative position of said rotatable member.

4. In a computing machine having a traveling carriage and a group of registers comprising a plurality of juxtaposed wheels for each denominational order and wherein said group of registers is shiftable laterally to different operative positions, resilient means urging said group of registers in one lateral direction, a rotatable member having steps on the periphery thereof, said steps being located at different radial distances from the center thereof, and cooperating with said group of registers to prevent said resilient means from moving the group of registers in said one lateral direction, and means controlled by said carriage for operating said rotatable member to bring the different steps on the periphery thereof into operative relation to said group of registers so that said resilient means may move said group of registers laterally step by step in accordance with the rotative position of said rotatable member.

5. In a computing machine, a register group comprising a frame supporting a plurality of registers, a set of differential actuators so arranged that the actuators are normally in operative alignment with the wheels of one of the registers, a cycling general operator for moving said actuators to run amounts into the wheels of the aligned register, resilient means urging said register group toward a lateral position for operatively aligning the wheels of another of the registers with said set of actuators, retaining means for holding said register group in its normal position, means for operating said retaining means in such manner that said resilient means may move said register group as aforesaid, and means in part operatively connected to said frame which supports the registers for preventing cycling of said general operator at all times when the wheels of one or another of the registers are not operatively aligned with the set of differential actuators.

6. In a computing machine, a register group comprising a frame supporting a plurality of registers, a set of differential actuators so arranged that the actuators are normally in operative alignment with the wheels of one of the registers, a cycling general operator for moving said actuators to run amounts into the wheels of the aligned register, a one-revolution clutch for operatively connecting said general operator to a source of power, means for effecting a lateral shift of said register group to bring the wheels of another one of said registers and the set of differential actuators into operative alignment,

and means comprising a first member connected to move laterally with said register frame and a second member constructed and arranged to cooperate with said one-revolution clutch, said first and second members having parts which are coengageable only when the wheels of any one of the registers are in operative alignment with the actuators whereby when the register group is in a position such that the wheels of none of the registers are operatively aligned with the actuators, the second member will act to prevent engagement of the one-revolution clutch and thereby prevent cycling of the general operator.

7. In a computing machine, a register group comprising a frame supporting a plurality of registers, a set of differential actuators so arranged that the actuators are normally in operative alignment with the wheels of one of the registers, a cycling general operator for moving said actuators to run amounts into the wheels of the aligned register, a one-revolution clutch for operatively connecting said general operator to a source of power, means for effecting a lateral shift of said register group to bring the wheels of another one of said registers and the set of differential actuators into operative alignment, and means comprising a first member connected to move laterally with said register frame and a second member constructed and arranged to cooperate with said one-revolution clutch and to be moved transversely of said first member whenever said clutch is engaged, said first and second members having parts which are coengagedable when the wheels of any one of the registers are in operative alignment with the actuators and which parts are coengaged during a cycle of the machine to thereby prevent lateral movement of said first member and consequently lock the register group in its selected position during the cycle.

8. In a machine of the character described having a cycling general operator, the combination with numeral types, and a letter-feedable carriage cooperative therewith, of a register group comprising a plurality of sets of computing wheels, a set of total-reading feelers normally retracted from but tending to move to engage the wheels of one of said sets of wheels, means for effecting a relative shift between said register group and said set of feelers to operatively align one or another of said sets of wheels with said set of feelers, a universal restorer for said set of feelers tending to move away from said feelers and normally latched in position to oppose engagement of said feelers with any of said sets of wheels, a latch operable to condition said restorer for release, and additional means associated with said restorer for preventing release of said restorer (even though said latch is operated) at any time when none of the sets of wheels and said set of feelers are operatively aligned.

9. In a machine of the character described having a cycling general operator, the combination with numeral types, and a letter-feedable carriage cooperative therewith, of a register group comprising a plurality of sets of computing wheels, a set of total-reading feelers normally retracted from but tending to move to engage the wheels of one of said sets of wheels, means for laterally shifting said register group to operatively align one or another of said sets of wheels with said set of feelers, a universal restorer for said set of feelers tending to move away from said feelers and normally latched in position to oppose engagement of said feelers with any of said sets of wheels, a latch operable to condition

said restorer for release, a first member arranged to move laterally with said register group and a second member constructed and arranged to cooperate with said restorer, said first and second members having complementary parts which are coengageable only when the wheels of any one of said sets of wheels are in operative alignment with said feelers, whereby when the wheels of none of the sets of wheels are operatively aligned with the feelers, the second member will act to prevent release of said restorer even though said latch is operated.

10. In a credit balance computing machine, a plurality of register groups, each group comprising a plurality of registers and each register comprising a plurality of wheels, a set of differential actuators for each register group, means for shifting any one of said register groups independently of the other register groups to bring the wheels of one of the registers of the shifted group into operative alignment with the set of differential actuators for said group, a cycling general operator for running indexed amounts into the wheels of the selected register, means for conditioning the selected group so that the selected register thereof will receive the indexed amounts either positively or negatively, and means for correcting the lowest order wheel of the selected register for a difference of one unit when the wheels of said register pass from a positive to a negative total or vice versa.

11. In a credit balance computing machine, a plurality of register groups, each group comprising

ing a plurality of wheels for each denominational order, a set of differential actuators for each register group, a carryover trip lever for each wheel, a set of carryover devices for each register group, means for shifting any one of said register groups independently of the other register groups to bring one of the wheels for each denominational order of the shifted group into operative alignment with the set of differential actuators for said group and to also bring the carryover trip levers associated with the selected wheels into operative alignment with the set of carryover devices, a cycling general operator for running indexed amounts into the selected wheels of the selected register group, and means for introducing a fugitive one to the selected wheels of the selected group in any shifted position of the group.
